BINDING POST

James C. Dawson, Jr., Kirkwood, Mo.

Application February 18, 1943, Serial No. 476,271

2 Claims. (Cl. 129—12)

The present invention relates to a binding post of plastic material for loose leaf books and more particularly to a novel construction including a post, holding elements for book covers, and a lock washer adapted to cooperate with one of the holding elements and the post to accommodate a book of varying thickness.

A particular object of the invention is to provide a post adapted to present a smooth surface to the leaves to be inserted in the book.

A further object is to provide a binding element having limited rotary movement with respect to the post, but adapted to be locked at any point along the length of the post.

A further object of the invention is to provide a binding post and associated parts of light material, such as plastic, that is available at the present time.

In the drawing:

Fig. 1 is a top view of a book with binding posts in position;

Fig. 2 is a sectional view drawn on the line 2—2 of Fig. 1;

Fig. 3 is a sectional view on the line 3—3 of Fig. 1;

Fig. 4 is a sectional view on the line 4—4 of Fig. 3;

Fig. 5 is a view of the top of the cover binder;

Fig. 6 is a bottom plan view of the binding element without the lock washer; and,

Fig. 7 is a vertical sectional view of the binding element without the lock washer.

In general the invention relates to a novel loose leaf book consisting of two binding covers 10 and 13, binder posts connecting these, and incorporated in the posts and covers for locking the covers at any distance from each other to hold a desired number of loose leaves.

In Fig. 2 there is shown a top cover 10 of a conventional loose leaf book, and a bottom cover 11.

The covers include a foundation 21 of wood or other fairly stable material, and a covering 22, which may be of cloth or imitation leather, and is cemented to the foundation in the conventional manner.

At 15 the top cover 10 is hingedly attached to a clamping member 12 by means of the covering 22, which covers the clamping member 12 in the same manner as it does the member 10.

The construction of the bottom cover, in general is similar to that of the top cover. The assembled book will include the conventional holes 25 extending through the leaves.

Binding posts 32 have circular base heads 31

adapted to be received in annular slots 30 in the foundation of the member 13, dogs 36 adapted to be wedged into the foundation of the member 13, and threads 42 to engage threads 41 of internally threaded rings 40. Thus the posts 32 are securely held in the member 13 against any possible movement with reference to that member.

Each of the posts 32 has a longitudinally extending groove 60 and a longitudinally extending threaded segment 61 adjacent the groove. The combined grooves and threaded segments together occupy 180° or less of the surface of the post.

The inner surface of the portion 12 has annular depressions 45 to receive the split lock washers 46.

Each of the binding elements 49 consists of a head 50 having projecting ears 51 against which the fingers may exert a twisting effort, and a lower extending sleeve 52. A dog 53 is adapted to move oscillatably in a keyhole slot 55 of the portion 12. The sleeve 52 has a groove 56 to receive the projecting lip 57 of a split lock washer 46. The lock washer 46 is adapted to expand over the end of the sleeve 52, until its lip engages a groove in the sleeve, into which it springs. This washer permits rotary movement of the binding element but prevents axial displacement thereof out of the element 12.

On the inner circumference of the element 49 there is a threaded segment 65. The threads in this segment are in the preferred form, heavier than the threads in the segment 61 so that upon engagement, there is a binding action between the two. For many conditions, however, adequate binding is effected by the expanding forces of the leaves, particularly when plastics are used for the elements.

Operation

Upon installation of the posts, they are secured to the portion 13 by means of the elements 40 and 31, securely imbedded therein. There is no chance here of movement either angularly or longitudinally. The posts are inserted so that the threaded portions and groove portions face inwardly and toward each other. The sheets are then placed over the posts. By the stated disposition of the posts, the sheets are not frayed or torn by contacts with the threaded portions of the posts, nor may they be displaced relative to each other by engagement with the irregular surfaces.

The upper cover is then placed over the sheets, with the binding elements turned so that their threaded segments 65 engage in the grooves 60,

whereupon the upper cover with the binding elements may readily move axially along the posts until they make a clamping action against the sheets. At this point, the binding elements are twisted to the limit permitted by engagement of the dogs 53 in the slots 55. This twisting effects engagement of the segmental threads 65 with the threads 61 on the posts.

The difference in size of the threads on the posts and the binding element in combination with the friction caused by the expanding pressure of the sheets, which the compressed book exerts, secure a locking action which would only be released by the application of a decided twisting effort exerted against the ears 51.

What is claimed is:

1. A binding post for a loose leaf book comprising means for locking one end immovably in a book cover, the main body of said post having two adjacent longitudinal segments, one of said segments being threaded, the other segment being grooved, and a means for locking another book cover in any position longitudinally of said post, said means comprising a large ring, a collar projecting therefrom, a dog projecting from said collar, said collar being grooved near the inner end, and a split lock washer having an inwardly projecting lip adapted to expand over the end of said collar and to spring into the groove thereof, said ring having an internal threaded portion, said portion having an angular width no greater than that of the grooved segment, whereby upon disposition of the portion in the groove the means may be displaced longitudinally on the post, the internal threads on said portion being larger than the threads on said post, the threads of said portion being engageable with the threaded segment upon angular movement of the ring about the

post, said engagement being adapted to hold the ring against axial displacement on the post, and means limiting the angular movement of the ring on the post to the compass of said segment.

5. 2. A binding post for a loose leaf book comprising means for locking one end immovably in a book cover, a main body, said body having two longitudinal adjacent segments, one of said segments being threaded, the other being grooved, 10 a second book cover, and a means for locking said second book cover in any position longitudinally of said post, said second book cover having a hole, a portion of said hole being of larger diameter than the rest of said hole, and a locking means adapted to extend into said hole and outside of said cover comprising a ring, a collar, and a lock washer adapted to fit into the portion of said hole of larger diameter than the rest of said hole, said ring having an internal threaded portion, said 15 portion having an angular width no greater than that of the grooved segment, whereby upon disposition of the portion in the groove the means may be displaced longitudinally on the post, and means limiting angular movement of the ring on the post to the arc of the post included by the longitudinal segments thereon, the threads on said post and on said ring being of different size and thereby being adapted upon meshing with each other to bind said locking means and said 20 post, said limiting means including a dog projecting from said collar and restricting the angular movement of said locking means with respect to said second book cover to the arc of the enlarged portion of the hole in said book cover, the 25 inner end of said collar being shaped to receive said lock washer.
